Inventor.
William Henry Southorne.

UNITED STATES PATENT OFFICE.

WILLIAM HENRY SOUTHORNE, OF NORTH SHIELDS, ENGLAND.

FURNACE FOR HEATING METAL ARTICLES AND THE LIKE.

1,347,719.

Specification of Letters Patent. Patented July 27, 1920.

Application filed December 27, 1918. Serial No. 268,518.

To all whom it may concern:

Be it known that I, WILLIAM HENRY SOUTHORNE, a subject of the King of Great Britain and Ireland, residing at North 5 Shields, in the county of Northumberland, England, have invented certain new and useful Improvements in or Relating to Furnaces for Heating Metal Articles and the like, of which the following is a specification.

This invention relates to furnaces for heating metal articles and the like and is more particularly intended for furnaces for hardening or annealing steel tools, gages 15 and other articles, the said improvements having for their principal object to insure the uniform heating of the articles under treatment and thereby to obviate the tendency to distortion of the said articles. At 20 the same time a uniform degree of hardness or temper throughout the articles treated is secured.

According to my invention, I provide the furnace with a table or bottom capable of 25 being revolved, on which table or bottom the articles to be treated are placed, and I so arrange the heating appliances that the flame does not impinge upon the article on the table or bottom.

30 The table or bottom is so supported that it can be readily removed and replaced or renewed, without dismantling or disturbing the body of the furnace.

The upper surface of the table or bottom 35 may be corrugated or roughened so that the air or gases in the furnace have free access to the under sides of the articles being treated.

One method of carrying out my invention 40 is illustrated on the accompanying drawing, in which:—

Figure 1 is a front elevation of the furnace:

Fig. 2 is a side elevation of same:

45 Fig. 3 is a plan of same, and,

Fig. 4 is a section on the line A—A Fig. 1.

The same symbols of reference denote the same parts in the various views.

50 *a* is the body of the furnace, which is preferably provided with an outer metal casing *b*, supported by legs *c*, or by some other suitable stand. The roof *d* of the furnace chamber is preferably arched. A circular hole *e* is provided through the floor of 55 the furnace, and in the hole is mounted a revolving table or bottom *f*.

The upper portion of the table *f* is preferably of larger diameter than the lower portion, thus forming a lip *f*¹, which projects over the hole *e* and prevents the escape of 60 the hot air or gases.

The upper surface of the table *f* is corrugated or roughened as shown at *g*, thus insuring free access of the air or gases to the under side of articles placed on the table. 65

The table *f* rests upon a plate or carrier *h* fixed on a vertical shaft *j*, by the set screw *k* or by other suitable means. The plate *h* is provided on its upper surface with a pin or projection *l* which fits into a correspondingly 70 shaped recess *m* in the under side of the table *f*, thus insuring the table revolving with the plate. *n* is a bracket acting as a bearing for the shaft *j*, and supporting the plate *h* and the table *f*. 75

A worm wheel *o* is fixed on the shaft *j* and gears with a worm *p* on the horizontal shaft *q*, which is carried by brackets *r*, *r*, *s* and is a driving pulley fixed on the shaft *q*.

The furnace is heated by means of a 80 Bunsen burner *t* which may be arranged on one side of the furnace. The burner is so arranged that the flame travels across the under side of the roof and down the opposite side of the furnace, and does not impinge directly upon the article on the table *f*.

u is the gas inlet, and *v* the air inlet to the burner *t*. The products of combustion pass out of the furnace by the passage *w*. 90 *x* is the door closing the mouth *y* of the furnace. The mouth *y* is made large enough to allow the table *f* to be removed from the carrier *h* and replaced or renewed without dismantling or interfering with the body 95 of the furnace.

In general it will be understood that I do not confine myself to the details of construction hereinbefore described, as the details may be varied considerably within a 100 fair interpretation of my claim.

What I claim as my invention and desire to secure by Letters Patent of the United States of America is:—

In a furnace for hardening and annealing 105 tools, gages and the like, a furnace chamber formed with an arched roof and concave sides, a removable rotatable table forming the bottom of said chamber, a reduced portion forming the bottom of the table, a circular hole in the bottom of the chamber into which the reduced portion projects, a car- 110

rier beneath said table, a shaped recess in the top of said carrier, a similarly shaped projection on the bottom of the reduced portion of the table adapted to engage said recess, means for supporting and rotating said carrier, an opening at one end of said chamber closed by a door, a passage leading from the top of said chamber at the other end through which the products of combustion pass and heating means comprising a

Bunsen burner projecting into the top of one of the concave sides of said chamber, for the purposes described.

In testimony whereof I affix my signature in presence of two witnesses.

WILLIAM HENRY SOUTHORNE.

Witnesses:

ARTHUR TURNER,

CHARLES STEPHEN GARDNER.
